FIG.1

FIG.2

FIG.3

INVENTOR
FRANKLIN S. GOODSPEED
BY
J. M. G.
ATTORNEY

UNITED STATES PATENT OFFICE.

FRANKLIN S. GOODSPED, OF NEW YORK, N. Y., ASSIGNOR TO WESTINGHOUSE LAMP COMPANY, A CORPORATION OF PENNSYLVANIA.

LAMP WRAPPER.

Application filed December 1, 1925. Serial No. 72,463.

This invention relates to cartons for incandescent electric lamps and particularly to a carbon adapted to enclose a plurality of lamps.

5 An object of the invention is the provision of a carton adapted to receive and resiliently support a plurality of incandescent lamps or other fragile articles in such a manner that they may withstand shipment 10 and handling without breakage.

Another object of the invention is the provision of a carton of a collapsible or knockdown type which may be quickly and easily assembled so as to constitute a carton 15 to enclose and support one or more lamps to prevent breakage of the glass parts thereof or a rupture of the lamp filaments through accidental impacts or jars.

A further object of the invention is to 20 provide a carton for supporting a pair of lamps such as automobile, tail or head-light lamps so that such lamps may be sold in pairs and retained by the purchaser in safety against accidental breakage until 25 used.

A still further object of the invention is to provide a carton for lamps of the miniature type on which may be marked the rating or other data and safely shipped and 30 conveniently displayed in a shipping and vending device, such as set forth in copending application, Serial Number 72,440, filed December 1, 1925, and assigned to the same 35 assignee as is the present invention.

35 By reason of the extremely fragile character of a lamp bulb and the delicate filament therein, it is necessary to exercise great care in packing such lamps for shipment or other handling to insure against breakage. 40 Furthermore, when providing a container or wrapper for miniature or flash-light lamps, which are of relatively low cost, it is desirable to provide a container of a cheap and effective construction.

45 The present invention provides a container which meets the above requirements in that is relatively low in cost, easily assembled and of sufficient strength to permit comparatively rough handling without injury to the 50 contents.

A carton embodying the present invention which is adapted to enclose a pair of lamps may be made from a single sheet of material having platforms integral therewith and so

arranged that when the carton is made up 55 the platforms are disposed between surrounding walls of the carton. Apertures are provided in the platforms through which a base of each of the lamps is inserted and thus held in a given position. The cartons may be marked on the outer side with the voltage or other data necessary to indicate the character of the enclosed lamps. 60

The invention will be more fully understood by reference to the accompanying 65 drawings in which;

Fig. 1 is a blank from which the present carton is formed.

Fig. 2 is a view showing the blank folded to partly assemble the carton preparatory to 70 the insertion of lamps therein and

Fig. 3 is a perspective view of the carton when closed about the lamps.

The illustrated embodiment of the present invention comprises a single sheet of 75 material which may be set up to enclose one or more lamps without the necessity of securing the edges by paste or other means, such as stapling, or the like. The present 80 container or cartons may be of any desired form and, as shown, are constructed from a sheet of sufficiently rigid foldable material, initially punched out in the form of a blank 10, and creased or scored as shown in Fig. 1. This blank may be creased at 85 11, 12, 13 and 14 to provide walls 15, 16, 17, 18 and a flap 19. The flap may be provided with portions 21 and 22 which, when the container is closed, constitute the end 90 walls thereof. The wall 16 is provided with flaps 23 and 24 and the wall 18 is provided with flaps 25 and 26. These flaps serve to add rigidity to the ends of the carton when the portions 21 and 22 are closed. These 95 last mentioned portions are provided with tucking flaps 27 and 28 respectively to hold or lock the portions 21 and 22, or top walls of the carton, in place.

For the purpose of supporting lamps within a container, the wall 15 is provided 100 with an extended portion 29 having oppositely disposed extensions or platforms 31 and 32. The platforms are provided with apertures 33 and 34 respectively, of such dimensions as to snugly fit the base 105 portions of the lamps to be inserted therein. The platforms 31 and 32 are made to have an area equal to the interior transverse

cross-section of the container and thus when the same is closed, the walls thereof firmly engage with the platforms and support the same against lateral movement.

5. The present form of carton may be quickly assembled and lamps may be inserted to the apertures and the platforms 31 and 32 when the carton is partially formed. The walls thereof may then be disposed about the 10 lamps in a wrapping operation and the tucking flaps 27 and 28 may be inserted to lock the carton.

When the carton is closed it provides a relatively rigid and self-supporting structure.

15. It will be noted that the extension 29, which is shown integral with the wall 15, carries the platforms 31 and 32. This extension, when the carton is closed, makes a contact with the wall 18 thereof, thus adding to the 20 strength of the interior structure which supports the lamps. By reason of the portions of the platforms the lamps are surrounded by a relatively resilient disk like member which dissipates many shocks or jars which 25 would otherwise be imparted to the lamps and, therefore, they are held without danger of injury.

The advantages of a quickly assembled container as herein described will be evident 30 from the foregoing and although a preferred embodiment of the invention is shown and described herein it is to be understood that modifications may be made therein, such as providing a separate internal lamp-holding 35 structure and securing the same to the walls of the carton without departing from the scope and spirit of the invention as set forth in the appended claims.

What is claimed is:

40. 1. A lamp wrapper comprising a sheet of material including four side walls, an extended portion on one end of said sheet, apertured extensions on opposite sides of said portion bendable to constitute platforms 45 for lamps, said sheet being foldable about said platforms to constitute a container for lamps.

50. 2. A lamp wrapper comprising a sheet of material including four side walls, an extended portion on one end of said sheet, apertured extensions on opposite sides of said portion bendable to constitute platforms for lamps, said sheet being foldable about said platforms to constitute a container for

55 lamps, and covers for the ends of said container.

3. A lamp wrapper comprising a sheet of material including four side walls, an extended portion intermediate opposite end of one of said side walls, extensions integral 60 with said portion, each of said extensions having an aperture to receive a lamp base and serve as a platform therefor, said side walls being foldable to constitute a container and said extensions being so disposed as to engage the walls of said container and resiliently support lamps supported thereby. 65

4. A lamp wrapper comprising a sheet of material including four side walls, an extended portion intermediate opposite ends 70 of one of said side walls, extensions integral with said portion, each of said extensions having an aperture to receive a lamp base and serve as a platform therefor, said side walls being foldable to constitute a container 75 and said extensions being so disposed as to engage the walls of said container and resiliently support lamps supported thereby, and end covers for said container.

5. A lamp wrapper comprising a sheet of 80 material including four side walls and a flap for overlapping one of said walls, an extended portion on the side wall to be secured to said flap, extensions integral with said portion, each of said extensions having an 85 aperture to receive a lamp, said sheet being foldable to provide a container for lamps.

6. A lamp wrapper comprising a sheet of material including four side walls and a flap for overlapping one of said walls, an extended portion on the side wall to be secured to said flap, extensions integral with said portion, each of said extensions having an 90 aperture to receive a lamp, said sheet being foldable to provide a container for lamps 95 and end covers for said container.

7. A lamp wrapper comprising a sheet of material including four side walls, an extended portion on one end of said sheet, apertured extensions on opposite sides of said 100 portion bendable to constitute lamp supports, said sheet being foldable about said supports to constitute a lamp container.

In testimony whereof, I have hereunto 105 subscribed my name this 25th day of Nov. 1925.

FRANKLIN S. GOODSPEED.
